UNITED STATES PATENT OFFICE.

JAMES F. MARVIN, OF FORT McDOWELL, ARIZONA TERRITORY.

IMPLEMENT FOR EXTRACTING CARTRIDGE-SHELLS.

SPECIFICATION forming part of Letters Patent No. 235,444, dated December 14, 1880.

Application filed August 18, 1880. (Model.)

To all whom it may concern:

Be it known that I, JAMES F. MARVIN, of Fort McDowell, in the Territory of Arizona, have invented a new and Improved Implement 5 for Extracting Cartridge-Shells, of which the following is a specification.

It frequently occurs that the flanged heads of cartridge-shells pull off and the shells are left in the barrel, from which it is difficult to remove them. This is specially liable to occur with cartridges that have been extracted several times.

The object of my invention is to furnish a device by which such headless shells can be 15 readily extracted; and the invention consists in a slotted tube flanged at one end and provided with an expansion-pin for spreading the tube after its insertion in the cartridge. The extractor is applied by insertion in the shell 20 expanded by closing the breech of the gun, so that when the breech is again opened the shell is drawn out.

In the accompanying drawings, forming part 25 of this specification, Figure 1 is a perspective view of my improved device, and Fig. 2 is a longitudinal section of the same as applied to a cartridge.

Similar letters of reference indicate corresponding parts.

30 A is a tube, preferably of steel, of a diameter for entering a cartridge-shell snugly, and formed with a flange at one end, as at a. This tube is slotted lengthwise from near the flange a to the opposite end, there being two or more of such slots; and the outer end of the tube 35 which is divided by the slots is formed tapering, as shown, so that it may readily enter the cartridge. The surface of the tube behind the

tapered end is recessed to form shoulders or projections, as at b, which will give a better 40 hold upon the cartridge; but these are not essential.

The tube is fitted with a loose pin, c, which, if desired, may be retained by a screw entering a longitudinal slot in the pin, as at d, so 45 that the pin may slide lengthwise. The aperture of the tube is tapered, the larger portion being at the flanged end; or the pin c may be tapering, so that the tube shall be expanded when the pin is forced inward.

In using the device it is inserted into the headless shell in the barrel and the breech closed, which will force pin c in and expand the tube A, so that when the breech is again 50 opened the usual cartridge-extractor takes behind the flange a and draws the tube and shell out together.

The tube can be released from the shell by driving pin c outward to loosen the tube. This 55 may be done by inserting a separate pin, or the pin c may be made of sufficient length to extend through the cartridge, as shown.

This extracting device is simple and effective, and will save the trouble heretofore experienced in removing headless shells from guns.

Having thus described my invention, what I claim as new, and desire to secure by Letters Patent, is—

A cartridge-extractor consisting of the tapered slotted tube having flange a, the shoulders b, and expansion-pin c, substantially as shown and described.

JAMES F. MARVIN.
